MAIL CHUTE LOCK

George A. Bridgman, Rochester, N. Y., assignor
to Cutler Mail Chute Company, Rochester,
N. Y., a corporation of New York

Application April 3, 1951, Serial No. 219,010

3 Claims. (Cl. 70—77)

1

The present invention relates to mail chutes and more particularly to locks therefor that insure them against tampering and against access by other than Government agents and persons authorized by them to clean and repair the chute and maintain it generally in good working order.

Mail chutes are commonly built in sections, one to a floor of the building, and each with an intermediate letter opening or mail drop arranged at a convenient height. The chute proper or conveying channel is continuous as to its rear and side walls, being solidly secured against the building wall usually by means of blind headed bolts. The front, however, is displaceable to give access to the interior from floor to ceiling for the purposes first above mentioned and also to dislodge clogs of mail matter that occasionally occur. Also, to quickly make apparent the existence of such a clog, the front is made transparent and, in each floor section embodies upper and lower removable glass panels. The top of the upper panel slidably interlocks vertically with the ceiling structure and the bottom of the lower panel similarly interlocks with a base at or near the floor. The central adjacent ends of the two come to near abutment within a fixed wall bracket frame to which the main chute channel is secured and spanning the front of this frame and cooperating therewith to conceal, restrain, and confine these panel ends in fixed position is a displaceable locking bar that thus controls the whole floor section. It is this locking bar with which the present invention is concerned.

The invention has for its general object to provide a locking bar of this character that will be simple, convenient to handle and secure in its functioning.

A further object is to provide a key controlled locking bar that is removable from and replaceable to its operative or locking position but can 40 not be carelessly left unlocked when the key is withdrawn.

Another object of the invention is to provide means for actively ejecting the bar from such seemingly attached position when it is not, in fact, locked securely in that position.

These and other desirable objects may be attained in the manner disclosed as an illustrative embodiment of the invention in the following description and in the accompanying drawings 50 forming a part hereof, in which:

Fig. 1 is a front elevation of a complete floor section of a mail chute provided with a locking bar constructed in accordance with and illustrating one embodiment of the present invention;

2

Fig. 2 is a fragmentary, enlarged vertical section taken transversely through the bar and contiguous parts on the line 2—2 of Fig. 1;

Fig. 3 is a horizontal enlarged section through the main chute channel and upper front panel on the line 3—3 of Fig. 2;

Fig. 4 is a similar section on the same line through the panel alone as when removed;

Fig. 5 is an end or top plan view of the lower 10 element of the section and the locking bar including the main chute channel and its panel, the corresponding upper parts being removed and certain details being shown in broken, horizontal section;

Fig. 6 is a horizontal central section, partly broken away, of the locking bar taken on the line 6—6 of Fig. 1 on the scale of Figs. 2 and 5;

Fig. 7 is a rear elevation, partly broken away, of the locking bar and on the same scale; and

Fig. 8 is a fragmentary rear view of the locking bar body showing the receiving opening 20 therein for the lock barrel.

The same reference numerals throughout the several views indicate the same parts.

Referring more particularly to the drawings, W indicates the finished wall of the building in which the chute is erected. Imbedded therein to come flush with the surface thereof are a pair of vertically disposed angle beams 10 and at an intermediate point between floor and ceiling there is secured to these angles by bolts 12 a rectangular supporting frame 14. A lower vertically disposed sheet metal chute channel 16 fits closely within this frame at its upper end which latter terminates short of the upper edge of the frame and is riveted thereto on back and sides as indicated at 18. The channel is thus supported in suspension, its lower end cooperating in continuation with a suitable between-floor section including a base 19. It is open at the front and a short distance back from the front edge 20 of each side wall the sheet material thereof is doubled into a crimp to provide two inwardly projecting shoulders 22 (Fig. 3). These form 30 seats for the rearward support of the removable front panel the body of which consists of a heavy plate of glass 24. The glass is paneled in a frame comprising hollow sheet metal side moldings 26 and connecting rails 28 at top and bottom. The latter is not shown but is identical.

The upper chute element 30 is substantially of the same formation as the lower element 16 and similarly disposed except that its lower end, within bracket frame 14, is tapered slightly so that 45 it wedges into the throat of lower channel 16.

as shown in Fig. 2 and covers the upper edge of the latter to form a perfect letter shed. The upper end cooperates suitably in continuation with a between-floor installation at the ceiling including a ceiling piece 32. It is closed at the front by another separate and removable panel 34 embodying as before side moldings 36 and end cross rails 38. The top end of this upper panel is thrust upwardly into the ceiling piece 32 with which it interlocks against outward movement while the rail 38 at the lower end rests upon a forward cross bar 40 that constitutes the front of the rigid rectangular frame 14. The rear face of this cross bar is inclined downwardly and rearwardly toward the interior of the chute as indicated at 42 to prevent descending letters from engaging the upper edge of the panel 24 and to completely insure this shedding protection bosses 44 are added at the ends to overhang the side moldings 26 which project farthest into the chute and also the shoulder seats 22 with which they make contact. The lower rail 38 of the upper panel rests upon the bar. The upper rail 22 of the lower panel is positioned just beneath the bar.

It will thus be seen that, with the upper end of the upper panel slidably interlocked behind the ceiling piece 32 and the lower end of the lower panel similarly interlocked with the base piece 19 and both abutting the cross rail 40 against any vertical movement while they are in their seats 22, both panels may be made secure against removal through forward tilting of their adjacent ends. For this purpose there is provided a removable and replaceable locking bar 48 which masters the situation. In the present embodiment it is pressed from heavy sheet metal to provide a hollow body having rearwardly turned marginal flanges all around. The end flanges 50 and adjacent portions of the top and bottom flanges 52 fit over reduced portions 54 (Fig. 5) on forward extensions of the side walls of bracket frame 14 which reductions (in dotted lines) provide shoulders 56 against which the edges of the flanges neatly abut. When the locking bar is so in place, the longitudinal flanges 52 engage over and under the cross rails 38 and 28, respectively, of the upper and lower panels which rails are made wide to project into the locking bar for this purpose.

At the center of the bar is an opening 58 (Fig. 8) which is occupied by the threaded barrel 60 of a Yale type rotary lock 62 secured on the inside by a nut ring 64. The cylinder 66 of this lock projects rearwardly beyond the barrel and terminates in an undercut circular head 68 opposite edges of which are machined off into flat, parallel faces 70. When the key 72 fitting cylinder 66 is turned right to an extreme stopped position as in Fig. 6, these flat faces 70 are vertically disposed and may pass closely between two spaced fixed lugs 74 and 76 projecting forwardly from cross bar 40 of frame 14 which occurs when the unlocked locking bar is applied to the chute panels. When the key is subsequently turned left 90° (which is its limit of movement, Fig. 5) the head 68 rotates with the cylinder and locks behind two shoulders 78 on the respective lugs 74 and 76, and the panels are made secure against forward movement and removal.

The barrel 60 cannot be unscrewed from the interiorly arranged nut ring 64 because it is provided with a flat face 80 fitting a corresponding irregularity 82 in the opening 58 provided for it in the locking bar as appears in Fig. 8.

The tumbler pins in the lock cylinder are so arranged that when the key is in the unlocked

position of Fig. 6 it cannot be withdrawn which is common practice in such locks and prevents the operator from leaving the chute with the key in his possession but with the device unlocked.

5 In the practice of the present invention, however, means are also provided to prevent the operator from applying the locking bar without locking it and departing with the key forgetfully left in the lock also. This provision at the same time tends to keep the key and locking bar together when they are detached from the chute.

To these ends, the lock barrel 60 also passes through a plate 84 fitting closely within the rear open side of the locking bar 48 and held down by the nut ring 64. Extending rearwardly from one end thereof is a flange 86 which, in turn, is flanged again to form a table 90 parallel with the plate and locking bar. A leaf spring 92 is fixed to this table as by screw 94 to project normally toward the lock cylinder 66 in the plane of the head 68 thereof. Its squared end comes opposite and in close proximity to a flat face 70 of the head as shown in Figs. 6 and 7 and when, as there, the cylinder is unlocked and the key cannot immediately be withdrawn or fall out, this spring 92 must be flexed and displaced inwardly or outwardly out of the plane of cylinder head 68 before the key may be turned to locking position and withdrawn. This requires a voluntary effort when the whole locking device is detached from the chute and perhaps laid aside and the key and locking bar will otherwise remain together.

But when the locking bar with the parts in the unlocked position of Figs. 6 and 7 is applied to the chute in the manner previously described, lug 74 on the cross bar of the bracket frame is in position to depress the spring 92 as shown in Fig. 5 and hence it is automatically released to permit the normal rotation of the lock cylinder and the locking function set forth.

In addition to this, when the locking bar is so applied to the chute frame, if the key is not turned to locking position to complete the operation, the spring 92 is sufficiently strong to forcibly eject the locking bar and when the pressure of the operator's hand is withdrawn it will fall to the floor reminding him of the unsafe condition and the fact that he has left the key in the lock.

It is seen from the foregoing disclosure that the above mentioned objects of the invention are well fulfilled. It is to be understood that the foregoing disclosure is given by way of illustrative example only, rather than by way of limitation, and that without departing from the invention, the details may be varied within the scope of the appended claims.

What is claimed is:

1. A locking device for the removable front panels of mail chutes embodying a bracket frame adapted to embrace and support the channel members of a chute section, a removable and replaceable locking bar spanning said frame and interlocking at its ends with forward portions 60 of side walls thereof, a key controlled lock carried by the locking bar and operatively cooperating with a portion of the frame when its key is turned in one direction to secure the bar thereto and confine said panels within the frame and against the channel members, means normally tending to eject the locking bar from such position on the frame, said ejecting means being energized by the act of applying the locking bar to the frame, said lock on the locking bar embodying a threaded barrel extending through

the bar and having a lock nut on the inside thereof and a rotary cylinder in the barrel terminating in an inner head; the bracket frame embodying a transverse front bar having a forwardly projecting undercut lug thereon with which the said cylinder head cooperates when turned to locking position; an angular post on the rear of the locking bar including a base secured beneath the barrel locking nut, and a leaf spring on the post in position to be depressed and tensioned by the lug and to constitute the ejecting means when the locking bar is adjusted to locking position on the frame.

2. A locking device for the removable front panels of mail chutes in accordance with claim 1 in which the leaf spring is also positioned to normally block rotation of the cylinder to locked position when the locking bar is separated from the bracket frame.

3. A mail chute including a fixed frame member, a removable panel, a retaining bar for securing said removable panel in fixed position on said frame member, a key operated lock mounted on

5
10

said retaining bar and effective when in normal locked position to retain said bar in fixed position on said frame member to retain said panel in the fixed frame, and spring means mounted on said retaining bar and cooperating with both said frame member and said lock, said spring means when in normal untensioned condition serving to prevent turning of said lock by its key, said spring means being tensioned by contact with said frame when said retaining bar is placed in normal position on said frame member to permit turning of the lock by its key.
